UNITED STATES PATENT OFFICE.

JAMES F. BAILEY, OF JACKSONVILLE, FLORIDA, ASSIGNOR OF ONE-HALF TO
FRANKLIN T. SUTHERLAND, OF JACKSONVILLE, FLORIDA.

WRENCH.

1,092,133.

Specification of Letters Patent.

Patented Apr. 7, 1914.

Application filed April 22, 1913. Serial No. 762,966.

To all whom it may concern:

Be it known that I, JAMES F. BAILEY, a citizen of the United States, residing at Jacksonville, in the county of Duval and 5 State of Florida, have invented certain new and useful Improvements in Wrenches; and I do hereby declare the following to be a full, clear, and exact description of the invention, such as will enable others skilled in 10 the art to which it appertains to make and use the same.

This invention relates to new and useful improvements in wrenches, and has for its object to provide a wrench which will be 15 easily and quickly adjusted.

Another object of my invention is to provide a wrench which will perform the same functions as an alligator wrench, but will provide one of the above class in which the 20 jaws are adapted to be adjusted.

A further object of my invention is to provide a wrench which may be easily and quickly adjusted by rotating the handle portion.

25 A still further object of my invention is to provide a wrench wherein the rotating portion of the handle will be made of sufficient size to insure proper adjustment of the jaws at all times.

30 With the above and other objects in view, I will now proceed to describe my invention in the following specification and accompanying drawings, in which,

Figure 1 is a side view of my improved 35 wrench in elevation; Fig. 2 is a longitudinal sectional view of my improved wrench; Fig. 3 is a detail view of a fragment of the jaw holding portions; Fig. 4 is a transverse sectional view taken on line 4—4 of Fig. 2; Fig. 40 5 is a transverse sectional view taken on line 5—5 of Fig. 2; Fig. 6 is a detail view of the jaw operating mechanism, showing the same with the jaws applied; Fig. 7 is a longitudinal sectional view of the modification of 45 my improved wrench; and Fig. 8 is a transverse sectional view taken on line 8—8 of Fig. 7.

Referring to the drawings by characters of reference, 1 indicates a stationary handle 50 portion, while 2 indicates the rotating handle portion. The jaw receiving portions are indicated at 3 and are provided adjacent their outer extremities with an enlargement 4. This enlargement is provided intermediate 55 its sides and adjacent its ends with an aper-

ture adapted to receive a bolt 5, which is secured therein by means of the nut 6.

The bolt 5 extends through the members formed on the portion 3 and is adapted to act as a pivot on which the jaws 7 and 8 are 60 adapted to swing. These jaws 7 and 8 are provided adjacent their outer extremities with the nut engaging surfaces 9. The opposite ends are extended, as clearly illustrated at 10, and provided with the angular 65 extensions 11, the use of which will be more fully hereinafter described. At the point 5, where the jaws are pivoted, they are cut away as will be seen upon referring to Fig. 6 of the drawings, and this cut away portion 70 extends from the point 12, at which the jaws meet, and extend rearwardly to the ends of the jaws.

The rotatable portion 2 of the handle is 75 inturned, as clearly illustrated at 13, and is adapted to form an annular collar around the sleeve 1 of the handle portion. Adjacent the extremity opposite the inturned portion, I preferably provide apertures through which screws 14 are adapted to 80 pass. These screws extend inwardly, as clearly illustrated in Fig. 2, and are screw threaded into the rotating member 15, which is provided with the longitudinal screw threaded aperture 16. A shoulder 17 is provided around the outer periphery of the rotating member 15, against which the rotating member 2 of the handle is adapted to 85 abut. A reduced portion 18 is formed integrally with the rotating member 15 and 90 extends into the member 1 of the handle portion. This reduced portion 18 terminates, as is clearly illustrated in Fig. 2, and forms a shoulder 19 against which the portion 1 of the handle abuts. Intermediate the 95 shoulder 19 and the inner extremity of the reduced portion, I preferably provide an annular groove 20, through which the pins 22 are adapted to extend, as will be more fully hereinafter described.

In the fixed sleeve 1 I preferably provide 100 the two semi-cylindrical sections 23 and 24, which terminate at their outer extremities in the arms 25 and 26, which form the jaw receiving portion previously referred to as 3. 105 These semi-cylindrical portions are provided with longitudinal grooves which form a longitudinal aperture through their center when they are in position. Pins 27 are adapted to extend through apertures in these semi- 110

cylindrical members, and their ends are adapted to project into apertures formed in the sleeve 1. These apertures in the sleeve 1 are formed substantially in the middle of 5 said sleeve, so that they will come in direct alignment with the apertures in the semi-cylindrical portions. I also provide apertures adjacent one end of the sleeve, which are adapted to receive the ends of the pins 10 22, these pins 22, as previously described, being adapted to coöperate with the annular grooves in the rotating sleeve 15 and hold said sleeve firmly in place.

A plunger 28 is provided adjacent one extremity with a reduced portion 29 which terminates in an enlarged cylindrical portion 30, having screw threads around its periphery. This cylindrical portion 30 is adapted to be received in the screw threaded apertures 16 of the revolving member 15, and it will be seen that upon rotation of the member 15 the plunger 28 will be caused to slide longitudinally through the grooves formed in the semi-cylindrical members. The end 20 25 of the plunger 28, opposite the end 30, is preferably enlarged, as clearly illustrated in Fig. 6, and provided with upstanding portions 31 which extend outwardly from the surface of the plunger and are adapted to 30 engage the angular portions 11 formed on each of the jaws. These portions 31 are provided with cam faces 32, which engage the angular extensions on the jaws and cause the same to open or close as the operator may 35 desire when the device is in use.

The construction of the handle portion of the modification is substantially the same as that above described. The main difference between the modification and the above 40 45 is that the movable jaw is rigidly secured to the plunger, so that upon rotation of the handle direct adjustment of the jaw is secured.

While in the foregoing I have shown and 45 described the preferred embodiment of my invention, I wish it to be understood that I may change the specific arrangements of parts without in any way departing from the spirit and scope of my invention.

Having thus fully described my invention, 50 what I claim is:

1. A wrench comprising a cylindrical sleeve, semi-cylindrical halves secured within the sleeve, extensions formed at the ends 55 of said semi-cylindrical halves, a plunger

slidable longitudinally through said semi-cylindrical halves, a revolving portion, said revolving portion being internally screw threaded, screw threads carried by one extremity of the slidable plunger, jaws pivotally secured intermediate the extensions, cam faces formed at the inner extremities of the jaws, cam faces carried by the slid- 60 able plunger at the extremity opposite the screw threaded end, said cam faces being 65 adapted to coöperate with the cam faces on the jaws, whereby adjustment of the jaws is obtained.

2. A wrench comprising a cylindrical sleeve, semi-cylindrical halves secured within the sleeve, extensions formed at the ends of the semi-cylindrical halves, a plunger slidable longitudinally through said cylindrical halves, an enlarged screw threaded portion formed at one end of the plunger, lateral extensions formed at the opposite end of said plunger, said lateral extensions being provided with cam faces, jaws pivotally secured between the extensions, a revolving portion, said revolving portion being internally screw threaded and cam faces formed on the jaws and adapted to coöperate with the cam faces on the plunger, the internal screw threads in the revolving portion and the threads on the enlarged portion 85 of the plunger being adapted to coöperate and thereby provide a means for the adjustment of the jaws.

3. A wrench comprising a fixed cylindrical sleeve, semi-cylindrical halves within 90 said sleeve, extensions formed at the upper extremities of the semi-cylindrical halves, jaws pivotally secured intermediate the extensions, a plunger slidable through the semi-cylindrical halves, an enlarged screw 95 threaded portion formed at the inner extremity of the plunger, a rotatable member, said rotatable member being internally screw threaded and adapted to coöperate with the enlarged portion on the plunger, a 100 revoluble sleeve secured to the rotatable member, and means at the end of the plunger opposite the enlarged portion to adjust the jaws when the sleeve is revolved.

In testimony whereof I affix my signature 105 in presence of two witnesses.

JAMES F. BAILEY.
